UNITED STATES PATENT OFFICE.

LUCIUS E. WEAVER, OF EAST HAMPTON, CONNECTICUT, ASSIGNOR TO THEOPHILUS KING, OF BOSTON, MASSACHUSETTS.

SEWING-MACHINE SHUTTLE.

1,320,516.

Specification of Letters Patent.

Patented Nov. 4, 1919.

Application filed November 15, 1918. Serial No. 262,704.

To all whom it may concern:

Be it known that I, LUCIUS E. WEAVER, a citizen of the United States, residing at East Hampton, in the county of Middlesex, and State of Connecticut, have invented new and useful Improvements in Sewing-Machine Shuttles, of which the following is a specification.

This invention relates to a sewing-machine shuttle having a bobbin chamber adapted to receive a ready-wound bobbin composed of a paper cop-tube and a winding of thread thereon.

The invention has for its object first, to provide a shuttle of this character with improved means for controlling the rotation of the bobbin and preventing it from rotating loosely and delivering loose thread.

The invention also has for its object to fully utilize the space in the bobbin chamber for the storage of thread, so that the maximum yardage of thread may be contained in the shuttle, thus enabling the shuttle to be used for a relatively long period without replenishment.

The invention is embodied in the improvements which I will now proceed to describe and claim.

Of the accompanying drawings forming a part of this specification,

Figure 1 is a plan view of a shuttle embodying the invention, without the bobbin.

Fig. 2 is a section on line 2—2 of Fig. 1.

Fig. 3 is a sectional view of an ordinary form of ready-wound bobbin.

Fig. 4 is a plan view of the shuttle with a bobbin.

Fig. 5 is a section on line 5—5 of Fig. 4.

Fig. 6 is a perspective view, showing the tubular stud hereinafter referred to, and portions of the bobbin support.

Fig. 7 is a perspective sectional view of the parts shown by Fig. 6.

Fig. 8 is a perspective view, showing the split headed sleeve and the sleeve-expanding screw hereinafter referred to.

Fig. 9 is a perspective sectional view of the hub hereinafter referred to.

The same reference characters indicate the same parts in all of the figures.

The drawings show a shuttle body of the well known Wilcox and Gibbs type, the body including an annular wall 12 forming a circular bobbin chamber, and a bobbin support or cross bar 13, rigidly attached to the wall 12 and extending across one end

of the bobbin chamber, the opposite end of said chamber being open for the reception of a ready-wound bobbin, composed of a paper cop-tube 15 and an annular winding 60 16 of thread thereon.

To the support or cross bar 13, is rigidly attached a stud 17, arranged at the center of the chamber and constituting an axle on which a hub 18 is rotatable. Said hub is a 65 tube formed to enter and engage the cop-tube 15, the external surface of the hub being preferably non-cylindrical and adapted to positively engage the cop-tube 15, the hub being here shown as externally polygonal and having numerous salient angles adapted to indent the inner surface of the cop-tube.

I provide means detachably connected with the stud for confining the hub against 75 endwise displacement, frictional means being provided within the hub for preventing loose rotation of the hub and bobbin.

The stud 17 is tubular and provided at its inner end with an internal shoulder 20, 80 forming a seat for the head of a screw 21. 22 is a sleeve longitudinally split by slots 23 and formed to fit the bore of the stud 17. The sleeve 22 is provided with a holding-down head 24 overhanging a portion of 85 the hub 18. The sleeve 22 is internally threaded to engage the screw 21, which is formed to expand the sleeve into binding engagement with the bore of the stud 17.

The inner end of the stud 17 is provided 90 with an annular shoulder or enlargement 25, forming an inner spring abutment and a bearing on which the inner end portion of the hub 18 is adapted to rotate. The outer end portion of the hub is provided 95 with an internal annular shoulder 26, adapted to rotate on the outer end portion of the stud 17, said internal shoulder forming an outer spring abutment. 27 represents a helical spring interposed between 100 the inner abutment formed by the external shoulder 25 and the outer abutment formed by the internal shoulder 26. Said spring is adapted to hold the shoulder 26 in yielding frictional contact with the holding-down 105 head 24, and thereby prevent loose rotation of the hub and bobbin.

The described parts are adapted to be conveniently assembled, the spring 27 being first applied to the stud, the hub 18 being 110 next applied to the stud and spring. The split sleeve 22 is then inserted in the stud

from the outer end thereof, and the screw 21 is finally inserted in the stud from the opposite end. The hub is now confined against endwise displacement on the stud, 5 and loose rotation of the hub and bobbin is prevented by the coöperation of the spring 27, the internal shoulder 26, and the holding-down head 24.

It will be seen that the ready-wound 10 bobbin does not require the usual heads applied to opposite ends of the hub. This is due to the fact that the hub 18 is confined against endwise displacement and is prevented from rotating loosely by means 15 located entirely within the hub, and therefore within the cop-tube 15, so that no space external to the bobbin is required for the reception of frictional means to prevent loose rotation of the bobbin. Practically 20 the entire distance between the inner and outer ends of the bobbin chamber may, therefore, be utilized for the storage of thread, the bobbin being correspondingly enlarged or lengthened.

25 I claim:

1. A sewing-machine shuttle comprising a body having a bobbin chamber, and a bobbin support at one end of the chamber, the opposite end being open, a stud fixed to said support and arranged at the center of the chamber, a hub rotatable on said stud and formed to enter and engage the cop-tube of a ready-wound bobbin inserted in the open end of the chamber, the stud being tubular, 30 and provided at its inner end with a screw-head seat, and hub-confining means detachably connected with the stud and including an internally threaded split sleeve fitting the bore of the stud and having a holding-down 35 head overhanging a portion of the hub, and a screw adapted to expand said sleeve into binding engagement with the stud and having a head formed to bear on said seat, frictional means including said holding-down 40 head being provided within the hub for preventing loose rotation of the hub and bobbin.

2. A sewing-machine shuttle comprising a body having a bobbin chamber, and a bobbin support at one end of the chamber, the opposite end being open, a stud fixed to said support and arranged at the center of the chamber, a hub rotatable on said stud and formed to enter and engage the cop-tube of a ready-wound bobbin inserted in the open end of the chamber, means detachably connected 50 with the stud for confining the hub against endwise displacement, said means including

a holding-down head overhanging a portion of the hub, and frictional means within the hub for preventing loose rotation of the 60 hub and bobbin, said frictional means including said holding-down head, an internal shoulder formed in the hub, and a spring arranged to yieldingly press said internal shoulder against said holding-down head. 65

3. A sewing-machine shuttle comprising a body having a bobbin chamber and a bobbin support at one end of the chamber, the opposite end being open, a tubular stud fixed to said support and arranged at the center of the chamber, said stud having at its inner end an external shoulder forming an inner spring abutment and a hub bearing, and an internal shoulder forming a screw-head seat, a split internally threaded sleeve fitting the 75 bore of the stud and provided at its outer end with a holding-down head, a screw adapted to expand said sleeve into binding engagement with the stud, and provided with a head adapted to bear on said seat, a hub 80 formed to enter and engage the cop-tube of a ready-wound bobbin inserted in the open end of the chamber, said hub being formed at its inner end to rotate on the external shoulder of the stud, and provided at its 85 outer end portion with an internal shoulder adapted to rotate on the outer end portion of the stud, said internal shoulder forming an outer spring abutment, and a spring interposed between said inner and outer abutments and adapted to hold said internal hub shoulder in yielding frictional contact with said holding-down head, and thereby prevent loose rotation of the hub and bobbin.

4. A sewing-machine shuttle comprising a 95 body having a bobbin chamber, and a bobbin support at one end of the chamber, the opposite end being open, a stud fixed to said support and arranged at the center of the chamber, a hub rotatable on said stud and 100 formed to enter and positively engage the cop-tube of a ready-wound bobbin inserted in the open end of the chamber, and means detachably connected with the stud for confining the hub against endwise displacement, 105 frictional means being provided within the hub for preventing loose rotation of the hub and bobbin, the hub being provided with a non-cylindrical external surface formed to indent the inner surface of the cop-tube. 110

In testimony whereof I have affixed my signature.

LUCIUS E. WEAVER.
